EYE SET FOR DOLLS

Nicholas Popovich, Teaneck, N. J., assignor of
one-third to Joseph A. Taferner and one-third
to Leo J. Schlitzer, both of New York, N. Y.

Application August 3, 1933, Serial No. 683,463

5 Claims. (Cl. 46—40)

This invention relates in general to eye sets for dolls and artificial figures, including eye members which are mounted within the head of a doll or the like to rotate in eye openings or sockets and simulate natural movement of the eyes as in opening and closing thereof. More particularly the invention relates to eye sets of this character which comprise a supporting means or bar which is secured in the doll head adjacent the eye opening and on which are mounted eye members and means for holding and rotating them in the eye sockets or openings.

Difficulty has been encountered heretofore in attaching glass eyeballs to mountings, especially because the eye balls easily crack or chip and cannot be bent, or penetrated with fasteners; but glass eye members are preferable to eye members formed of other material because the glass eyeballs more closely simulate the natural or anatomical eye and can be more easily made.

One object of my invention is to provide a novel and improved simple and inexpensive glass eyeball mounting including a spherical glass eyeball and a split metal clip embracing the eyeball and having an integral lateral or radial extension for connecting the clip to a pivot rod for rotatably mounting the eyeballs on a supporting bar.

Another object is to provide such a glass eyeball mounting wherein said clip shall comprise a split ring to embrace or surround an eyeball and having integral lateral extensions at its ends for both securing said ends together and attaching the clip to a pivot rod, whereby the attachment of a glass eyeball to a pivot rod shall be simple, and inexpensive, reliable and durable.

Other objects are to provide an eye set wherein said lateral ends of said clip shall cooperate to form a polygonal socket which opens radially of the clip and slidably receives the polygonal end of a pivot rod, whereby said clip shall be slideable longitudinally of the pivot rod to permit lateral adjustment of the eyeballs in the eye sockets in a doll head, and said clip and eyeballs shall rotate with the pivot rod to simulate opening and closing of the eyes; and to obtain other advantages and results as will be brought out by the following description.

Referring to the accompanying drawing in which corresponding and like parts are designated throughout the several views by the same reference characters.

Figure 1 is a rear elevation of an eye set em-

bodying my invention, showing it in a doll head which is illustrated in vertical section.

Figure 2 is a transverse vertical sectional view on the line 2—2 of Figure 1.

Figure 3 is a horizontal sectional view partially in side elevation, taken on the line 3—3 of Figure 1.

Figure 4 is a detached composite perspective view of the pivot member and one of the clips for supporting an eyeball.

Figure 5 is a perspective view of one of the clips, showing it in the condition preparatory to attaching it to an eyeball.

Figure 6 is a front elevation of the assembled eyeball and clip.

Figure 7 is a rear elevation thereof, and

Figure 8 is a transverse sectional view on the line 8—8 of Figure 6.

Specifically describing the illustrated embodiment of the invention the reference character A designates a doll head of known construction which is formed of penetrable material and has the usual eye sockets B in the face portion thereof. In each of the eye sockets is arranged an eye member 1 mounted to rotate to simulate opening and closing of the eyes, these eye members being mounted on a pivot member or rod 2 which is in turn pivotally mounted in a bracket 3 which is secured on a supporting member or bar 4.

The supporting bar 4 described and claimed in my copending application Serial No. 672,116 is shown in the form of a flat strip of ductile metal having end sections 5 which are provided with integral prongs 6 for penetrating the material of the doll head. The end sections 5 are connected by an extensible intermediate or central section 7 which consists of a plurality of sinuous rod-like structures each substantially uniform in cross section throughout its length and including a plurality of alternately reversely curved or angularly disposed portions which can be elongated or extended and partially straightened by exerting pressure on the end sections 5 tending to separate them. Preferably the sinuous sections 7 merge into each other integrally at their ends and at spaced intermediate points 70 along the longitudinal median line of the bar. The end sections 5 are formed with shoulders 8 each in opposed and aligned relation to one prong 6 to form a bearing point or abutment for a tool for exerting tension on the end sections. The supporting bar is normally of a length less than the distance between the opposite side walls of the doll head, as shown in Figure 4, and in ap-

plying the supporting bar to the doll head, tension is exerted on the end sections 5 so as to pull them apart, elongate the bar and drive the prongs 6 into the walls of the doll head as shown in Figure 1. The shoulders 8 enable pressure to be applied to the prongs 6 in direct line with the prongs and uniformly on all prongs to avoid twisting of the end sections as the prongs are driven into the doll head. Obviously, the bar 10 will be located adjacent the eye sockets B and in approximately equidistantly spaced relation from each of the eye sockets.

The bracket 3 for supporting the pivot member 2, is also described and claimed in my said copending application Serial No. 672,116 and comprises a single strip of resilient sheet metal which is folded on itself and provided with a reentrant groove 9 at the fold. The free extremities of the strip are disposed in approximately parallel relation and have grooves 10 to receive the central sections 7 of the supporting bar, and notches 100 to straddle one of the junctions 70 of the sinuous sections. The bracket is attached to the supporting bar by inserting 25 the free ends of the strip between the sinuous sections before the bar is elongated, one sinuous section being arranged in the groove 10 of each end and the notches 100 straddling one of the junctions 70; and as the supporting bar is elongated during inserting thereof into the doll head, the sinuous sections are drawn together into the grooves 10 so as to firmly clamp the ends of the bracket strip between them as shown in Figures 1 and 2 of the drawing. The bracket 3 is formed with a slot 12 which extends transversely of the groove 9; and the bracket 3 also has a spring tongue 11 integral therewith and looped outwardly therefrom with its free end extending through said slot 12 transversely of the groove 9.

40 The reentrant groove 9 of the bracket serves as a bearing for the pivot member 2 which is shown in the form of a rod having its end portions flattened or polygonal in cross section as indicated at 13 and disposed in axial alignment with each other, and the pivot rod 2 is inserted 45 into the groove 9 with the spring tongue 11 behind the rod and tending to influence it outwardly of the groove. The flat ends of the pivot rod slidably support the eye members 1.

50 An eyeball 14 consisting of a hollow sphere preferably formed of glass has on its spherical surface the representation of a pupil and iris as indicated at 15. The eyeball 14 is mounted on the pivot rod 2 by a clamp 16 which is in the form of a metal split ring which includes two sections 17 each constituting a segment of a hollow sphere of the same diameter as the eyeball 14. The ends of the split ring 16 are provided with lateral extensions 18 and 19 which 55 are channel shaped and adapted to nest one with the other with their channels facing each other, as clearly shown in Figures 4 and 5. The flanges of one of the lateral extensions, in the present instance the extension 18, are wider 60 than the flanges of the other extension 19 and are bent over the extension 19, as indicated at 65 20 for connecting the extensions together. When the lateral extensions 18 and 19 are connected together as shown in Figure 4 they form 70 between them a socket 21 which extends radially of the clip to slidably receive one polygonal end 13 of the pivot rod 2. The clip 16 is preferably formed of one piece of metal and the two sections 17 may be sprung into angular relation to 75 each other, as shown in Figure 5, by bending of

the metal at the juncture 22 of the two sections 17.

In assembling the eyeball and clip, the two sections 17 of the clip are sprung apart as shown in Figure 5, after which the eyeball 14 is set 5 between the sections and the sections are drawn together to embrace the eyeball. Due to the spherical configuration of the sections 17, said sections will snugly conform to the eyeball to firmly clamp the latter. The lateral extensions 10 18 to 19 are brought into nested relation, after which the flanges 20 of the extension 18 are bent over the extension 19 to secure the ends of the clip together and secure the clip around the eyeball. 15

In mounting the eye member in a doll head, each end 13 of the pivot rod 2 is slipped into the socket 21 of one of the eye members, it being understood that the socket and polygonal end 13 are of such dimensions that the eye member 20 may slide longitudinally of the pivot rod in both directions. The bracket 3 is then attached to the supporting bar 4 and the pivot rod is slipped into the groove 9 of the bracket. Thereafter, the eye members are set in the eye sockets B 25 and the supporting bar is secured in the head. The spring tongue 11 yieldingly influences the eye members into the eye sockets and the longitudinal sliding of the clips 16 on the pivot rod permits the eyeballs to adjust themselves to 30 various distances between the eye sockets.

The pivot rod 2 has the usual pendulum arm 35 24 connected thereto for rotating the eyeballs by action of gravity so as to move the eyeballs and the eye sockets into a position to simulate closing of the eyes when the doll is laid horizontally. The pendulum arm is provided with an extension 25 which abuts the spring tongue 11 to limit swinging movement of the pivot rod in the direction to rotate the eye members into open-eye position, the spring tongue 11 thus serving as a shock absorber or buffer. 40

45 Preferably, eyelashes 26 are secured to the eyeball 14 above the representation 15 of the pupil and iris, and the upper section 17 of the clip overlies the lashes and may be suitably colored to simulate an eyelid.

50 While I have shown and described my invention as embodied in certain details of construction it should be understood that the invention may be embodied in other details of construction without departing from the spirit or scope of the invention.

Having thus described my invention, what I claim is:

55 1. An eye member for dolls comprising a substantially spherical eyeball and a clip in the form of a split ring embracing said eyeball and having channel shaped lateral extensions at its ends with their channels facing each other to form a socket between them to receive a member for mounting the eye member in a doll head, the flanges of said channel shaped extensions being directly interlocked together to secure said clip around the eyeball.

60 2. An eye member for dolls comprising a substantially spherical eyeball and a clip in the form of a split ring embracing said eyeball and having lateral extensions at its ends formed with inter-engaging portions for directly connecting said extensions together to secure the clip on the eyeball and forming between them a socket to receive a member for mounting the eye member in a doll head. 70

3. In an eye mounting, a supporting means to 75

- be secured in a doll head, a pair of eye members and a pivot member having polygonal ends for mounting said eye members on said supporting means, each eye member comprising a substantially spherical eyeball and a clip in the form of a split ring embracing said eyeball and having lateral extensions at its ends that are channel shaped and disposed one within the other with their channels facing each other to form a socket between them, and the flanges of one of said extensions being bent over the other extension to connect said extensions together.
- 5 5. An eye member for dolls comprising a substantially spherical eyeball and a clip in the form of a split ring embracing said eyeball and having lateral extensions at its ends, said extensions being channel shaped and disposed one within the other with their channels facing each other to form a socket between them a member for mounting the eye member in a doll head and said extensions interlocking with each other to connect the ends of said clip together.
- 10 10. An eye member for dolls comprising a substantially spherical eyeball and a clip in the form of a split ring embracing said eyeball and having lateral extensions at its ends connected together to secure said clip around the eyeball
- 15 15. 4. An eye member for dolls comprising a substantially spherical eyeball and a clip in the form of a split ring embracing said eyeball and having lateral extensions at its ends connected together to secure said clip around the eyeball

NICHOLAS POPOVICH.
